Primary Examiner — Catherine Tuttle(74) *Attorney, Agent, or Firm* — Troutman Sanders LLP;
Ryan A. Schneider(57) **CLAIM**

The ornamental design for a cube kendama, as shown and described.

DESCRIPTION

FIG. 1 is a top perspective view of a kendama according to the present invention, where cooperating elements are fit together;

FIG. 2 is a top perspective view of the kendama of FIG. 1, where cooperating elements are separate;

FIG. 3 is a bottom perspective view of the kendama of FIG. 2;

FIG. 4 is a front view of the kendama of FIG. 1;

FIG. 5 is a back view of the kendama of FIG. 1;

FIG. 6 is a side view of the kendama of FIG. 1;

FIG. 7 is the other side view of the kendama of FIG. 1;

FIG. 8 is a top view of the kendama of FIG. 1; and,

FIG. 9 is a bottom view of the kendama of FIG. 1.

The dashed lines are for illustrative purposes only and form no part of the claimed design.
